CLAIM

The ornamental design for a beveled berm, as shown and described.

DESCRIPTION

FIG. 1 is a front view of a beveled berm base showing our new design, the rear view being identical thereto;

FIG. 2 is a left side view thereof, the right side view being identical thereto;

FIG. 3 is a top view thereof;

FIG. 4 is a bottom view thereof; and,

FIG. 5 is an upper front left perspective view thereof.

The dot-dash lines immediately adjacent the shaded areas represent a claim boundary and form no part of the claimed design. All other broken lines are directed to the portions of the beveled berm that form no part of the claimed design. The beveled berm is shown with a symbolic break in its length. The appearance of any portion of the beveled berm between the break lines forms no part of the claimed design.

1 Claim, 5 Drawing Sheets
